UNITED STATES PATENT OFFICE.

GEORGE F. HULLINGS AND DAVID P. MOORE, OF WASHINGTON, DISTRICT OF COLUMBIA.

STAPLE-AFFIXING MACHINE.

1,133,862.

Specification of Letters Patent. Patented Mar. 30, 1915.

Application filed October 10, 1914. Serial No. 866,096.

To all whom it may concern:

Be it known that we, GEORGE F. HULLINGS and DAVID P. MOORE, citizens of the United States, residing at Washington, in the District of Columbia, have invented certain new and useful Improvements in Staple-Affixing Machines, of which the following is a specification.

The present invention relates to improvements in staple affixing machines.

One object of the present invention, is the provision of a machine of this character which will accommodate and operate upon a flat strip of staples, the strip being fed into the magazine of the present machine and below the plunger, so that upon the driving movement of the plunger, the first staple will be severed and driven, while the second staple will have the prongs thereof bent in staple form simultaneously therewith.

A further object of the present invention, is the provision of a machine of this character in which the pawls for moving the strip and for holding it against a retrograde movement are so mounted as to be readily released from the strip to permit of the adjustment of the strip or the removal thereof from the machine without the necessity of cutting and forming the staples, and thus preventing the clogging of the machine.

A still further object of the present invention is the provision of a machine of this character which is simplified in its construction, the parts being made more durable and such machine being constructed to accommodate a reel of connected partially formed staples, so that such partially formed staples may be carried and readily attached to the present machine to be formed, severed and clenched by the plunger and other mechanism thereof.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a side elevation partly in section of the present machine,

the operating lever being broken away at the top as is also the head of the plunger. Fig. 2 is a sectional view through the magazine showing the feeding and retrograde preventing pawls in proper position relatively to the strip of staples, the feeding pawl being shown in section. Fig. 3 is a section taken on line 3—3 of Fig. 1. Figs. 4, 5 and 6 are detail views of the staple engaging end of the plunger. Fig. 7 is a top plan view of the machine, the forward portion of the base and magazine being broken away as well as the operating lever. Fig. 8 is a top plan view of a reel of the staple strip. Fig. 9 is a perspective view of the feed-in end of such strip. Fig. 10 is a section taken on line 10—10 of Fig. 2, such section being through the complete magazine.

Referring to the drawings, the numeral 1 designates the supporting member of the present device, which when properly mounted is supported upon a tubular pedestal (not shown), so that the rod 23 will be extended therethrough and connected to a foot treadle (not shown).

The forward projection 2 of the support 1 constitutes the base and support for the anvil 3, which is provided with the clenching recess 4. Formed integral with and projecting above the base 2, are the two lugs 5, which receive the removable bolt or supporting pin 6 for the bar 7 of the magazine 9. The bar 7 is provided as illustrated in Fig. 3, with the two parallel grooves 8, which form recesses to receive the prongs of the formed staple 47 carried upon the staple strip as illustrated in Figs. 8 and 9. These strips of staples are preferably formed so that the main body thereof have the prongs 48 in a plane with the body with the spaces 49 therebetween, so that when the prongs 48 are bent as will presently appear, they will produce the staple as 47.

Mounted in the free end of the magazine 9 for vertical reciprocating movement, is the plunger 10, which is provided with the guiding ribs 11, and a lower staple cutting and driving end 12. To the rear of the end 12 and formed integral therewith is a projection 13, which is recessed as at 14 (Fig. 4) to receive the prongs 48 of the staple strip 105 and to bend the same downwardly upon the reduced anvil end 7' of the strip 7. Also formed integral upon the rear face of the

plunger 10 at a point above the staple forming member or recess 14 thereof, is the double inclined lug 15, which operates the staple feeding member 31, as will presently 5 appear.

Surrounding the upper end of the plunger 10 is a spring 16, which under rides the head 17 of the plunger and thus holds the same elevated as shown in Fig. 1, while attached to the head 17 to operate the same 10 against the tension of the spring 16 to drive the plunger downwardly to cause the severance of the formed staple 47 from the strip and at the same time form the next succeeding 15 staple, is a lever 18, the opposite end thereof being pivoted at 19 to the supporting bracket 20. Two rods 21 are pivotally connected to the lever 18 intermediate of its ends and are in turn depended upon opposite 20 site sides of the reel 45 to engage the bar 22, which in turn is connected to the operating rod 23 heretofore described, a helical spring 24 surrounding such rod and normally exerting a tension to hold the lever 18 elevated 25 with the magazine 9 tilted to permit the introduction of an article to be stapled upon the anvil 3, the magazine as shown in Fig. 1 being illustrated as resting upon the anvil just previous to the final depression of the 30 plunger 10.

Mounted within the magazine 9 upon the pivoting pin 25, is the pawl actuating member 26, the same being provided with the end 27 disposed in the path of the lug 15 35 upon the up stroke, to cause the pawl 31 to be fed forward to cause the end 33 thereof to engage the strip of staples to move the same beneath the plunger, and further with the projection 28, which is disposed in the 40 path of the lug 15, so that upon the lowermost movement of the plunger 10, the pawl 31 will be retracted or moved toward the rear of the magazine so that the end 33 thereof will ride upon the strip to engage 45 the next succeeding staple. This member 26 is connected by a pin 30 to the pawl 31 so that the desired pivotal action may be imparted to the pawl 31 in its movement to and from the plunger 10. Mounted for 50 oscillation in the magazine 9 is a transverse shaft 34, which has fixed thereupon within the magazine, the retrograde preventing pawl 36, whose teeth 32 are disposed in the path thereof to engage the strip between the 55 respective prongs 48 in the space 49 adjacent the web thereof and thus prevent the withdrawal of the strip, or the retrograde movement thereof during the downward movement of the plunger 10 and the backward 60 movement of the pawl 31. The shaft 34 is shouldered as at 35, to receive a key (not shown), so that the shaft may be rocked to cause the pawls 36 and 31 to assume the position as shown in dotted lines 65 Fig. 2, lifting both strip engaging ends 32

and 33 out of engagement with the strip, so that the strip may be withdrawn or adjusted within the magazine freely.

Mounted upon the pin 39 within the magazine is a double-terminal spring, whose terminal 40 engages the pawl 31 to hold the end 33 thereof resiliently in engagement with the strip and upon the bar 7, while the terminal 41 engages the pawl 36 to hold its end 32 also resiliently upon the staple strip 75 and bar 7. It will be noted that the free end of the pawl 36 is projected between the staple engaging ends 33 of the pawl 31, and that the pawl 31 will have free movement during the actuation thereof by the member 26 and 80 also, so that the portion of said pawl 31 above the free end of the pawl 36 will be in the path thereof to be engaged so that the parts may assume the dotted line position as shown in Fig. 2. 85

Carried upon the rear end of the bar 7 are the two brackets 43 slotted at 44 to receive the pintle 45 of the reel or spool 45, which carries the strip 46 of flat staples. These reels are so constructed that from three to 90 five thousand staples are carried in a single strip, thus rendering it unnecessary to so often charge the machine as is the case where the short completed straight strips, as is now the practice, are used. 95

In machines using formed staples it is only practical to use from twenty-five to ninety-two to a strip, those in the ninety-two strip being inconvenient due to the tendency of the metal to twist the staples, and at the same time with staples thus formed, an exceedingly complicated machine is necessary to cut, and form the strip staples, the present machine doing away with this and operating upon a strip of herring-bone staples 100 which are formed flat, and can conveniently be rolled in a coil upon a reel, thus accommodating in a single reel from three to five thousand staples. 105

As before stated in order to facilitate the 110 operation of the present machine, a staple 47 is formed upon one end of each reel at the initial starting thereof, so that the same may be fed under the plunger 10, below the driving and cutting end 12 thereof, so that the first staple will not have to be formed when the plunger is driven down, thus presenting at the initial starting a staple to be severed and driven and finally clenched in the recess 4 of the anvil 3, the next succeeding 115 staple being so disposed that the prongs 48 thereof will fit within the recess 14 and thus be compressed upon the anvil portion 7' of the bar 7 to be upon the upward movement of the plunger 10, fed forwardly by 120 the feeding pawl 31 under the elevated plunger, thus assuming the position as shown in Fig. 1. By this means, the strip will successively be fed forward so that the present 125 mechanism will rotate the reel 45, according 130

to the distance between the staples, at each elevation of the plunger 10.

What is claimed is:

1. A staple affixing machine for operation upon strip staples having a magazine, staple controlling means therein, and manually controlled means for positioning the staple controlling means so that the strip of staples may be withdrawn from the magazine 10 through the feed-in end.
2. A staple affixing machine for operation upon strip staples having a magazine, a reciprocatory plunger mounted in the magazine, a staple feeding means mounted in the magazine and operated by the plunger, and manually operable means for affecting the feeding means to release the strip of staples to permit their withdrawal through the feed-in end of the magazine.
3. A staple affixing machine for operation upon strip staples having a magazine, a reciprocatory plunger mounted in the magazine, a staple feeding pawl mounted in the magazine and operated by the plunger, and manually operated means for releasing the pawl to permit the strip of staples to be withdrawn through the feed-in end of the magazine.
4. A staple affixing machine, including a magazine, a plunger mounted therein for reciprocation, means for feeding a strip of staples to present one staple at a time to the plunger as the plunger is reciprocated, and manually actuated means for releasing the feeding means from the staples to permit the withdrawal of the staples from the magazine.
5. A staple affixing machine, including a magazine, a reciprocatory plunger mounted therein, a pawl for feeding a strip of staples operated by the plunger, and a manually operable retrograde movement preventer mounted in the magazine and arranged in such relation to the pawl and strip of staples, 45 that when said preventer is disengaged from the staples, the pawl is also disengaged.
6. A staple affixing machine, including a magazine, a reciprocatory plunger mounted therein, a pawl for feeding a strip of staples operated by the plunger, a retrograde movement preventing pawl mounted in the magazine for engaging the strip of staples, said latter pawl being adjacent to the first pawl, and means for actuating the retrograde
- movement preventing pawl to release the strip of staples and to simultaneously release the first pawl from such strip of staples.
7. A staple affixing machine for forming, severing and clenching staples from a strip, including a base, an anvil having a staple 60 clenching recess, a magazine mounted upon the base for movement to and from the anvil, a reciprocatory plunger mounted in the magazine and having a staple severing and driving end and a staple bending and forming member, whereby upon the depression of the plunger, the outer staple is severed from the strip while the next succeeding staple is bent and formed, means mounted in the magazine and disposed to coöperate 65 with the plunger for feeding the staple strip forward upon the upward movement of the plunger, and manually controlled means for positioning said means so that the strip of staples may be withdrawn from the magazine.
8. A staple affixing machine for forming, severing and clenching staples from a strip, including a base, an anvil having a staple 70 clenching recess, a magazine mounted upon the base for movement to and from the anvil, a reciprocatory plunger mounted in the magazine and having a staple severing and driving end and a staple bending and forming member, whereby upon the depression of the plunger, the outer staple is severed from the strip while the next succeeding staple is bent and formed, a staple feeding pawl mounted within the magazine, means connected to the pawl and located in 75 the path of the plunger for actuating the said pawl into the staple engaging and staple feeding position, a retrograde movement preventing pawl mounted in the magazine and having its free end disposed adjacent to 80 the feeding pawl and for engagement with the strip of staples, and means for rocking the retrograde movement preventing pawl to elevate its free end and the feeding pawl both out of engagement with the strip.
9. In testimony whereof we affix our signatures in presence of two witnesses.
